UNITED STATES PATENT OFFICE.

RICHARD J. DONOVAN, OF AMBRIDGE, PENNSYLVANIA, ASSIGNOR TO
AMERICAN BRIDGE COMPANY, OF PITTSBURG, PENNSYLVANIA, A
CORPORATION OF NEW JERSEY.

RAKE CORNER OR KNUCKLE FOR STEEL BARGES.

No. 853,920.

Specification of Letters Patent.

Patented May 14, 1907.

Application filed March 16, 1907. Serial No. 362,695.

To all whom it may concern:

Be it known that I, RICHARD J. DONOVAN, of Ambridge, Beaver county, Pennsylvania, have invented a new and useful Rake Corner or Knuckle for Steel Barges, of which the following is a full, clear, and exact description, reference being had to the accompanying drawings, forming part of this specification, in which—

10 Figure 1 is a side elevation showing the end portion of a steel barge constructed in accordance with my invention; and Figs. 2, 3 and 4 are partial cross-sections on the lines II—II, III—III, and IV—IV respectively of Fig. 1.

15 My invention relates to the corner constructions of steel barges, and particularly to those wherein the upper portion of the corner is rounded or curved in cross-section. 20 Heretofore in such structures the corner plate has been curved from the top to the bottom, and it has been a difficult matter to prepare the plate and connect it with the corner piece running along the lower longitudinal corner of the barge.

25 My invention is designed to provide for the use of a corner portion which is rounded in its upper part and is of angular section in its lower part where it connects with an angle 30 which connects the side and bottom plates through the body of the barge.

35 In the drawings, 2 represents the upper part of the corner piece, which is curved longitudinally and transversely, and is preferably formed of a steel casting or a pressed plate. This portion is preferably recessed at the edges, as shown at 3, 3 to receive the rake plating 4 and the side plating 5 respectively. The remaining portion of the 40 corner piece is preferably formed of a pressed plate 6, which is formed with a curved or rounded cross-section in its upper portion and with an angular or square cross-section in its lower portion, as shown by the two sections, Figs 3 and 4. These portions gradually merge into each other, giving a corner plate which may be easily and cheaply 45 pressed and afford a rounded corner, while at the same time allowing a rolled angle to 50 be used along the lower side corner of the barge body.

In the drawing, 7 represents the rolled an-

gle, which extends along the inner edges of the side plating and the bottom plating, this angle being bent up to overlap the pressed 55 plate 6 on the inside of the side and rake plating respectively. The side and rake plating is of course riveted to the member 6 and also to the member 7 at their overlapping portions. 60

The advantages of my invention result from the peculiar corner plate or corner piece, which is of rounded cross-section in its upper portion and of angular cross-section in its lower portion. This gives the rounded 65 surface which is desirable above, while allowing a rolled angle to be used along the lower outer corner of the barge body. The corner piece may be formed in one or more sections, and changes may be made in its size and 70 shape without departing from my invention.

I claim:—

1. In barge construction, a corner piece between the side plating and rake plating having a curved cross-section in its upper 75 portion and an angular cross-section in its lower portion; substantially as described.

2. In barge construction, a corner plate overlapping the outside edges of the side plating and rake plating, and riveted thereto, 80 said plate having a curved cross-section in its upper portion and an angular cross-section in its lower portion; substantially as described.

3. In barge construction, a corner piece 85 having an upper section curved longitudinally and transversely, and the remaining section having a curved cross-section in its upper portion and an angular cross-section in its lower portion; substantially as described. 90

4. In barge construction, a corner piece arranged to overlap the side plating and rake plating, said piece being of curved cross-section in its upper part and of angular cross-section in its lower part, in combination with 95 an angle overlapping the side and rake plating on the inside; substantially as described.

In testimony whereof, I have hereunto set my hand.

RICHARD J. DONOVAN.
